Primary Examiner — Holly Baynham

(21) Appl. No.: 29/509,946

CLAIM

(22) Filed: Nov. 23, 2014

The ornamental design for a suitcase with hygienic products organizer, as shown and described.

Related U.S. Application Data

(63) Continuation-in-part of application No. 14/297,407, filed on Jun. 5, 2014.

DESCRIPTION

(51) LOC (10) Cl. 03-01

FIG. 1 is a front view of my suitcase design with a hygienic products organizer case/display stand therein, and with the suitcase shown in the closed position.

(52) U.S. Cl.

FIG. 2 is a first side view of the suitcase of FIG. 1.

USPC D3/274

FIG. 3 is a second side view of the suitcase of FIG. 1.

(58) Field of Classification Search

FIG. 4 is a top view of the suitcase of FIG. 1.

USPC D3/319, 273-274
CPC B65D 59/00
See application file for complete search history.

FIG. 5 is the suitcase of FIG. 1 shown in an open position, to expose the hygienic products organizer case/display stand that is releasably secured therein.

(56) References Cited

FIG. 6 is a top view of the opened suitcase of FIG. 5.

U.S. PATENT DOCUMENTS

504,840 A 9/1893 Krick
838,031 A 12/1906 Kirkpatrick
1,206,276 A 11/1916 Wallach
1,452,278 A 4/1923 Kind
1,521,260 A 12/1924 Trachtenberg
1,613,536 A 1/1927 Rose
